United States Patent Office

Des. 186,214

Patented Sept. 29, 1959

186,214

TRACK TYPE TRACTOR TREAD UNIT

Paul R. Francis, Los Angeles, Calif., assignor to Alloy Steel & Metals Company, Los Angeles, Calif., a corporation of California

Continuation of design application Serial No. 35,734, April 29, 1955. This application April 22, 1957, Serial No. 45,836

Term of patent 14 years

(Cl. D14—6)

FIG. 1.

FIG. 2.

Fig. 1 is a perspective view of a track type tractor tread unit illustrating my new design, and showing it from the top and one side thereof.

Fig. 2 is an enlarged top perspective view of a part of the track type tractor tread unit and showing it from one end and one side thereof.

This is a continuation of my copending design application Ser. No. D-35,734, filed April 29, 1955, entitled Pad for Endless Track, now abandoned.

I claim:

The ornamental design for a track type tractor tread unit, as shown.
